DISPENSING DEVICE

William W. Kelly, Cleveland, Ohio

Application January 6, 1933, Serial No. 650,426

7 Claims. (Cl. 34—21)

This invention relates to a dispensing device designed particularly for use in the retail sale of nut meats although adaptable to other commodities.

5 The principal object of the invention is to display the nuts or other commodities effectively and at the same time maintain them in condition for immediate consumption. A further object is to provide a device which will at the same time heat 10 the nut meats and permit the escape to the surrounding atmosphere of characteristic aroma designed to attract customers.

I am aware that prior to my invention dispensing devices for this class of commodities have 15 been provided with heating means such as an electric light bulb or the like and accordingly I do not claim this feature broadly but only the improved features and novel combinations of elements and arrangements of parts hereinafter described and claimed.

Fig. 1 is an elevation of a device embodying my invention; Fig. 2 is a plan view thereof; Fig. 3 is a central vertical section taken therethrough; Fig. 4 is a horizontal section taken above the base 25 and looking down; Fig. 5 is a horizontal section corresponding substantially to the line 5—5 of Fig. 3; Fig. 6 is a detail in plan of a hot air inlet member; Fig. 7 is a section on the line 7—7 of Fig. 6; Fig. 8 is a detail elevation of a partition 30 and circulation assembly; Fig. 9 is an elevation of the same assembly at right angles to Fig. 8 and Fig. 10 is a wiring diagram showing the connections of the various electrical devices.

Referring to the drawings numeral 10 indicates 35 generally a base member having formed therein a socket for receiving a receptacle for containing merchandise and a delivery platform 11 communicating by an opening closed by a door 12 with the interior of the receptacle. Within the base 10 is a conduit indicated generally by the numeral 13 communicating with the bottom of the receptacle and containing an electric heating means 14 and a pump or fan 15 driven by an electric motor 16.

45 The base 10 comprises a generally upright wall defining an elongated housing and being of generally cylindrical form provided with a lateral extension extending beneath the delivery platform 11. Within the central portion of the base 50 is a cylindrical upstanding member 17 extending nearly to the top of the base and having formed thereon a bead 18 upon which the hot air inlet member 19 is adapted to rest. Above the member 19 is a perforated plate 20 forming the bottom 55 of the receptacle. At the top of the member 17

an annular member 21 rests and affords a socket for the lower end of a glass cylinder 22 whose inner surface is preferably flush with that of the member 17. Within the member 17 and the glass cylinder 22 is received the lower cylindrical portion 23 of the partition assembly shown in detail in Figs. 8 and 9. Resting upon the top of the lateral extension of the base 10 and forming an upper closure therefor is the delivery platform 11, the lower end of which rests upon the perforated bottom plate 20. This platform is removable as are also the side plates 24. Attached to the platform 11 centrally thereof is a fin 25 the front vertical edge of which fits snugly against and forms a continuation of the partition plate 26 at 15 its lower end. The door 12 is provided with a slot 27 for limiting its upward motion by engagement with the lower edge of the annular member 21.

Air enters the base 10 through a suitable inlet 20 opening 28 under the influence of the pump 15 after which it passes through the conduit 13 by way of the heating element 14 and is emitted through an opening 29 into the hot air inlet 19 where it encounters a plate 30 and is distributed 25 outwardly, passing upwardly through openings 31 and thence through the perforated plate 20 into the receptacle. The partition 26 extends across the cylindrical member 23 dividing the latter as well as the cylinder 22 into two compartments. Secured to the member 23 at the top thereof and to the partition 26 is an inwardly and downwardly extending baffle partition 32 which is perforated so as not to interfere with the upward passage of air. Secured to the partition 26 is a perforated cage 33 composed of two semi-cylindrical portions secured one to each side of said partition and provided with a downwardly and outwardly extending frusto-conical baffle portion 34 and a cover 35 which may or 40 may not be perforated. Secured to the top of the partition 26 is a cross member 36 having downturned ends 37 adapted to engage over the upper edge of the glass cylinder 22. The cross member 36 extends at right angles to the partition 26 45 as indicated in Fig. 9 although it has been shown for convenience in Fig. 3 as extending parallel thereto. The downturned ends of the member 36 also serve the purpose of spacing the cover 38 from the cylinder 22 whereby to permit escape 50 of air. The cover 38 may also be provided with openings 39 for this purpose.

The exterior of the base 10 is spaced from the member 17 as will be seen by reference to Figs. 3 and 5 and within this space is positioned on a 55

suitable framework 40 a series of electric lights 41 above which are positioned lenses preferably colored for illuminating the surface of the cylinder 22. Any desirable color of lenses may be employed and means may be provided for changing colors if desired either by shifting lenses or providing different colors which may be turned on one at a time or all together.

By reference to Fig. 10 it will be seen that the motor 16 which drives the fan 15 is connected in series with a rheostat 42 and a portion 43 of the heating element 14 while a pilot light 44 is connected in parallel therewith and a suitable switch 45 which may be manually operated. It will also be seen that the electric lights 41 are connected in series with a portion 46 of the heating element 14 and a suitable switch 47. The main portions 48 and 49 of the heating element 14 are connected through a selector switch 50 which by connection with the contact 51 places the portion 48 in service, by connection with the point 52 places the portion 49 in service and by connection to the spaced contacts 53 and 54 places both in operation.

In use the cover 33 is removed and the receptacle on the two sides of the partition filled with different kinds of nuts or the like, the cover 35 preventing any of these from entering the cage 33 and the motor 16, lights 41 and heater 14 or any of them is placed in operation. Where only the lights are employed as will sometimes be the case the portion 49 of the heating element will be in operation and by the well known tendency of heated air to rise will cause a slight circulation through the receptacle, which in warm weather may be sufficient to maintain the nuts at the desired temperature. If the motor is also turned on but not the main portions of the heating element, air will circulate through the device at a much higher rate and heat will be provided by the heating element portion 43 and/or that 46. Normally, however, when the device is filled with nuts at low temperature it will be desirable for a time at least to place the heating elements 48, 49, or both, into operation in order to get best results. The perforated cage with the baffle in which it terminates at its lower end, together with the baffle partition therebelow form means for free circulation of heated air to all parts of the receptacle and provide for heating the nuts above the baffle partition to substantially even degree while separating the same into two bodies, one above and one below the said baffle partition, that below, which is soonest to be delivered, being subjected to heat in a somewhat greater degree. If the door 12 is slightly opened the delivery platform 11 and any nuts thereon may be kept warm.

From the foregoing it will be evident that I have provided a device of the character described which is well adapted for its intended purposes and while I have shown and described the preferred embodiment I wish it understood that I am not limited to the details thereof but only in accordance with the prior art and with the spirit and scope of the appended claims.

Having thus described my invention, what I claim is:

1. In a device of the class described, a receptacle having inlet means for air at the bottom

thereof, outlet means for air at the top thereof and a dispensing outlet at one side for removal of nuts therefrom, means for forcing heated air into and through said receptacle, a funnel shaped, horizontal baffle partition spaced above the bottom of said receptacle and a foraminous cage spaced above said baffle partition.

2. In a device of the class described, a receptacle having inlet means for air at the bottom thereof, outlet means for air at the top thereof and a dispensing outlet at one side for removal of nuts therefrom, means for forcing heated air into and through said receptacle, a funnel shaped, horizontal baffle partition spaced above the bottom of said receptacle and a foraminous cage spaced above said baffle partition and provided with a closed top and a flaring bottom.

3. In a device of the character described, an opaque base having set thereinto a receptacle of smaller bottom diameter than the diameter of the top of the base, the top of said base being provided with a flange extending above the bottom of said receptacle and radially spaced therefrom; electric lights in the space between said receptacle and said flange, a conduit communicating with said receptacle and having an electric heater and a pump therein, said lights being connected in series with a portion of said heating means.

4. In a device of the class described, a base comprising a socket for a display and heating receptacle and a delivery platform, receptacle forming means mounted upon said socket, said means being provided with a restricted air outlet at the top thereof; a closure separating said receptacle and said platform and when open permitting the passage of heated air whereby nuts remaining on the platform may be kept hot and means for supplying heated air to said receptacle.

5. As a sub-combination in a device of the character described, a substantially vertical partition plate carrying centrally a vertically extending foraminous, open bottomed, closed topped tube, said plate extending substantially radially of said tube, and said partition plate having attached thereto below said tube and spaced therefrom an inwardly and downwardly extending baffle partition, said baffle partition extending transversely of said tube.

6. As a sub-combination in a device of the character described, a vertically extending foraminated partition plate carrying a vertically extending foraminated tubular element, said plate extending substantially radially of said tube, said partition plate also carrying a foraminated baffle element extending transversely of said tube and spaced therebelow.

7. In a device of the character described, the combination of a container for nuts and from which leads a delivery outlet, a partition fitting within said container and dividing the same into a plurality of compartments each of which is in open communication with said delivery outlet, said partition having a foraminous bottom portion and including a foraminous tubular portion the lower end of which is disposed over and spaced from said bottom portion.

WILLIAM W. KELLY.
